UNITED STATES PATENT OFFICE.

WILLIAM I. DERRICK, OF DAVENPORT, IOWA, ASSIGNOR TO WESTCO-CHIPPEWA PUMP COMPANY, OF DAVENPORT, IOWA, A CORPORATION OF DELAWARE.

PUMP.

Application filed April 25, 1923. Serial No. 634,499.

This invention relates to rotary pumps and more particularly to the class of pumps having a rotor mounted in a casing.

- An object of the invention is to provide a pump with a rotor which engages liquid in an annular passage or passages and delivers it to a suitable discharge with a greater efficiency than pumps of this class have heretofore had.
- Another object of the invention is to provide an improved construction of pumps of this type in which a relatively larger quantity of water delivered may be increased or relatively higher pressures may be attained, or both.

These and other objects will be apparent from the drawings and specification.

In the drawings,

Figure 1 is a side elevation partly in section of the pump assembled.

Fig. 2 is a side elevation of the rotor.

Fig. 3 is a transverse section of the rotor.

Fig. 4 is a side elevation of the pump casting with the rotor removed.

Figs. 5 and 6 are sections of the pump taken on the lines 5—5 and 6—6 respectively of Fig. 4.

Fig. 7 is a view of the edge of part of the rotor.

The pump has a suitable base 1 and comprises a casing 2 formed with members 3, 4 which are held together by suitable bolts. The members 3, 4 of the casing have laterally extending tubular bosses 5, 6 respectively to receive the shaft 10. These bosses receive suitable packing material, thus forming a stuffing box closed by the nuts 13, 14 which surround the shaft 10 and are threaded into the bosses.

The bracket arms 7, 8 extend laterally from the sides of the casing and have apertures therein in axial alinement with the bosses or hubs 5, 6. These apertures are designed to receive suitable bearing members in which the shaft 10 may be rotated by any desired power means such as a motor (not shown). Secured to the shaft 10 in any suitable manner for rotation therewith is a rotor 11, which will be more fully described in the specification hereafter.

The member 3 has an outer peripheral wall 25 at an angle to the body portion, and a peripheral flange 22 in a plane paral-

lel to the body portion. The member 4 has a flange 23 offset from the body portion, a face of which bears against the face of the opposed flange 22 of the member 3. The annular flange 22 and 23 are recessed at 27 and are provided with a packing 24 disposed in said recesses to prevent leakage between the flanges. The recesses 27 are preferably of larger cross-sectional area than the packing so that the packing can be compressed and be formed to make a tight joint and yet will not prevent the faces of the flanges 22 and 23 from being in contact throughout substantially their entire area for a purpose to be more fully set forth hereinafter. The shoulder 26 formed around the body portion of the member 4 by the offset flange 23 is received inside and engages the outer wall 25 of the member 3. With this construction is formed a substantially liquid tight, disc-like opening in which the rotor 11 is mounted to be rotated by the shaft 10.

The opposed body portions of the members 3, 4 have annular passages 17, 18 formed therein leading from a common supply opening 15, connected to a suitable source of liquid, to a discharge opening 16 connected to a service line or other desirable line. The passages 17, 18 preferably are tapered, being progressively smaller in cross sectional area from the supply to the discharge opening. Near the periphery of the rotor and opposed to the passages 17, 18 are formed a multiplicity of blades 30 to engage the liquid in the passages 17, 18. These blades may extend in the passages 17, 18 but preferably they are formed in the rotor and their outer edges do not extend beyond the faces of the rotor. If desired, the blades may be formed by milling out pockets 32, leaving the ribs or blades 30 upstanding. The pockets 32 are of sufficient depth so that movement of the blades relative to the passages 17, 18 will effectively move and carry along the liquid therein. An efficient cross sectional shape of the passages 17, 18 is shown in the drawings, but this may be modified to vary the quantity of liquid delivered or the pressures developed during the operation of the pump to procure pumps suited to meet various conditions. The pockets 32 do not extend to the extreme edge of the rotor 11 but terminate a suffi-

cient distance radially inwardly therefrom to leave continuous annular surfaces 33 which rotate adjacent the body portions of the members 3, 4 and resist escape of liquid 5 from the passages 17, 18, the rotor casing members thus being in sufficient proximity to prevent any substantial quantity of liquid moving between them.

The rotor 11 has a substantially liquid-tight engagement with the body portions of the members 3, 4 of the casing to prevent leakage of any substantial amount of liquid radially inwardly from the passages 17, 18. Between the supply opening 15 and the discharge opening 16 is a deflecting member or cut-off 36 adapted to closely engage the face of the buckets on each side of the rotor to prevent liquid from passing from the discharge ends of the passages 17, 18 into the supply or suction ends of these channels except such liquid as may be carried past the deflecting members in the buckets of the rotor. The deflector closely engages the lateral face of the rotor and rotor buckets with 25 in the raceways and spans a sufficient number of the pockets or blades to substantially prevent the unrestricted flow of liquid between the face of the rotor and the deflecting means and to maintain relatively large pressure differentials between the outlet and the inlet ends of the raceways. It will be understood, of course, that the liquid retained in the pockets of the rotor as they pass the liquid deflecting means will be carried from the outlet end of the passage to the inlet end thereof without substantial loss in pressure which would result if liquid were permitted to flow between the blades and the deflecting means. By this means a relatively 30 high pressure differential is maintained during operation of the pump between the inlet and the outlet ends of the passages.

The provision of raceways on opposite sides of the rotor substantially relieves the 45 rotor from unbalanced lateral thrust which in pumps of this character operating to produce relatively high pressures is of considerable degree. In high pressure pumps having a raceway in only one side thereof, the 50 rotor may even be deflected laterally by these pressures which would destroy in part the close fit between the rotor and casing and limit the usefulness of the pump.

In the wall 25 of the member 3 of the casing I preferably form an additional passage 19 from the supply opening to the discharge opening, which is preferably tapered, growing smaller from the suction to the discharge opening. I also provide blades 34 similar 60 to blades 30 and pockets 35 between them in the edge of the rotor disc to engage the liquid in the passage 19. These pockets are also formed relatively shorter in length than the width of the rotor disc, thus leaving two 65 continuous annular faces 37 to engage the

wall 25 and resist the flow of liquid out of the passage. The provision of the channel 19 enables me to obtain relatively greater pressures and relatively larger volumes of liquid.

As it is essential that with my pump the casing and rotor be accurately positioned with respect to each other, I have designed a construction with which it is comparatively easy to insure such positioning. The member 3 75 of the casing with its flange 22 may be accurately made and the member 4 with its flange 23 may also be accurately made. By insuring the contact of the flanges 22 and 23, notwithstanding the packing between 80 them, the casing members may be easily assembled to properly position them with respect to the rotor.

In the normal operation of my pump, upon rotation of the rotor the blades 30 act 85 upon the liquid in the passages 17, 18, and the blades 34 act upon the liquid in the passage 19, moving it forward through the passages which are progressively decreasing in cross sectional area from the inlet to the outlet. Depending upon the relative proportion of the area of the passages and dimensions of the rotor blades, the water is delivered to the discharge side of the pump at a relatively high pressure or in a relatively 90 large volume and this with greater efficiency than heretofore has been attainable.

It will be noticed that while the rotor and casing members are so positioned as to prevent any substantial quantity of water passing between them, any liquid that may pass the sealing surfaces 33, 37 will be received in the channel 19 and be delivered into the discharge opening.

It will also be seen that the rotor may be 105 relatively thin, thus reducing the weight of the metal to be moved and requiring less power to move it.

As the rotor and casing walls are positioned closely together throughout a substantial area between the hub and annular passages 17, 18 the escape of water radially inwardly from the raceways is very greatly resisted and in fact is substantially prevented, and such liquid as may come between 110 the rotor and casing during the operation of the pump seems to act as a lubricant.

Similarly, the opposing faces of the rotor and casing outwardly of the passages 17, 18 and also the opposing surfaces between the edge of the rotor and the wall 25 of the casing are sufficiently close together to resist the passage of liquid and to prevent any substantial quantity of liquid from passing between them. However, due to pressures developed by this pump, any liquid that may be forced outwardly can be received in channel 19 and carried in it to the discharge duct.

It will also be noticed that the blades may be formed integrally with or attached to the 130

rotor and in their longitudinal dimension may be straight or curved, it being desirable, however, to have the blades disposed substantially at right angles to the liquid in the channel.

Furthermore, it is to be understood that the particular forms of apparatus shown and described, and the particular procedure set forth, are presented for purposes of explanation and illustration and that various modifications of said apparatus and procedure can be made without departing from my invention as defined in the appended claims.

15 What I claim is:

1. A pump comprising a casing, a shaft mounted therein, a rotor secured to the shaft, a plurality of annular passages in the casing adjacent the periphery of the rotor, said 20 passages having common peripheral supply and discharge ducts, and blades on the rotor for engaging liquid in said passages, said rotor and casing having a substantially liquid-tight running fit between said passages and liquid deflecting means having a close running fit with said blades and extending over a plurality of successive blades for deflecting liquid from said annular passages to said discharge duct and for maintaining 25 relatively great pressure differential between the outlet and the inlet ends of the passages.

2. A pump comprising a casing, a shaft mounted therein and carrying a rotor, a plurality of radially closed annular passages in 30 the casing adjacent the periphery of the rotor, said passages being connected to supply and discharge ducts and being of less cross sectional area progressively from the supply duct to the discharge duct, and blades 35 on the rotor to engage liquid in said passages.

3. A pump comprising a casing, a rotatable shaft mounted therein and having a rotor secured thereto, an annular passage 40 in the casing adjacent the periphery of said rotor and terminating in supply and discharge ducts, said passage having portions of different cross sectional areas between the supply and discharge ducts, blades on the 45 rotor to engage liquid in said passage and a liquid deflecting member having a close running fit with a plurality of said blades for deflecting liquid from the annular passage to the discharge duct.

55 4. The combination with a pump body and a cover forming a casing of a shaft mounted therein and carrying a rotor, the casing walls and rotor having a substantially liquid-tight engagement, a plurality of passages in the casing adjacent the edge of the 60 rotor, said rotor having blades thereon to engage liquid in said passages, supply and discharge ducts for supplying liquid to and receiving liquid from said passages, and liquid deflecting means closely cooperating

with said blades for deflecting liquid from said passages to said discharge ducts, said deflecting means being adapted to maintain substantial pressure differential between the outlet and inlet ends of the passage during 70 operation.

5. A pump comprising a casing, a shaft mounted therein and carrying a rotor, a plurality of annular passages in the side walls of the casing and opposed to the faces 75 of the rotor, blades carried by the rotor to engage liquid in said passages, the rotor and casing having a substantially liquid-tight fit radially inwardly of said passages, supply and discharge ducts cooperating with 80 the ends of said passages and deflecting means in said passages for deflecting liquid from each passage to a discharge duct and for maintaining substantial pressure differential between the inlet and outlet ends 85 of the passages during operation.

6. A pump comprising a casing, a shaft mounted therein and carrying a rotor, a plurality of annular passages in the side walls of the casing and opposed to the faces of the 90 rotor, blades carried by the rotor to engage liquid in said passages, the rotor and casing having a substantially liquid-tight fit radially inwardly of said passages, and supply and discharge ducts cooperating with the 95 ends of said passages, said passages having portions of less cross sectional area between the supply and discharge ducts.

7. A pump comprising a casing, a shaft mounted therein, a rotor secured to the 100 shaft, opposed annular passages formed in the side walls of the casing and adjacent the peripheral edge of the rotor, blades carried by the rotor to engage liquid in said passages, said rotor and casing having a substantially liquid-tight engagement between 105 said passages, a liquid deflector and stop at the discharge ends of said passages, and supply and discharge ducts for supplying liquid to and receiving liquid from said passages. 110

8. A pump comprising a casing and a rotatable disc therein, said casing having a plurality of independent annular passages formed therein adjacent the periphery of the rotor, independent annular series of radially 115 disposed blades formed on said disc to engage liquid in said passages, said disc and casing having a substantially tight fit whereby movement of liquid radially inwardly is resisted, and supply and discharge ducts co- 120 operating with said passages.

9. A pump comprising a casing and a movable rotor therein, said casing having a plurality of opposed annular passages adjacent the periphery of the rotor, the rotor 125 and casing having engaging portions at each side of said passages to form liquid seals, a passage in the casing opposite the peripheral edge of said rotor, radially disposed blades on the rotor to move adjacent said 130

passages, supply and discharge ducts for said annular passages, and a stop and liquid deflector of greater circumferential extent than the separation of said blades between 5 the discharge duct and the passages.

10. A pump comprising a casing and a rotor mounted for movement therein, said casing having a plurality of opposed annular passages, blades carried by the rotor to move adjacent said passages, supply and discharge ducts for said passages, said passages each having at least one portion of less cross sectional area between said supply and discharge ducts, said rotor and casing having 15 a sufficiently close fit to substantially prevent movement of liquid radially inwardly.

11. A pump comprising a casing, a shaft mounted for rotation therein and carrying a rotor, opposed annular passages formed in 20 the walls of said casing and provided with supply and discharge ducts, said rotor being provided with blades to engage the liquid in said passages, said passages being formed progressively smaller in cross sectional area 25 from their supply ends to their discharge ends, said rotor and casing being provided with means to substantially prevent movement of liquid radially inwardly, and a cut-off to prevent liquid passing from the discharge ends of said passages into the supply 30 ends.

12. A pump comprising a casing, a shaft mounted for rotation therein and carrying a rotor, independent annular passages formed 35 in said casing and provided with supply and discharge ducts, said rotor being provided with blades to engage liquid in said passages, said blades being disposed in a plurality of annular series, one series on the edge 40 and the other series being disposed in the faces of the rotor and adjacent the edge, said rotor and casing being provided with cooperating means to substantially prevent movement of the liquid radially inward and to 45 prevent liquid from passing from the discharge ends of said passages into the supply ends thereof.

13. In a rotary pump, a cylindrical casing, opposed annular passageways near the inner 50 periphery of the casing, a rotor fitting snugly within the casing and having pockets on opposite sides aligning with said passageways, and inlet and outlet ports communicating with said passageways.

14. A pump comprising a casing having two parallel circular fluid raceways and a common inlet and a common outlet for said raceways, and a rotor having an annular series of buckets in each raceway.

15. A pump comprising a rotor having an annular marginal series of blades in each lateral face and a casing forming therewith an annular channel, said casing on each side of each of said channels forming a substantially water-tight joint with the face of said

rotor on each side of said blades to form a pair of closed fluid raceways.

16. A pump comprising a rotor having an annular marginal series of blades in each lateral face thereof, a shaft for said rotor 70 and a casing having bearings for said shaft and comprising a section facing each side of said rotor and respectively having an annular channel therein opposite the series of blades, the said casing sections each forming a substantially water-tight joint with the corresponding face of the rotor on each side of the corresponding series of blades to form a pair of closed fluid raceways, said casing having a fluid inlet and outlet. 75

17. A pump comprising a rotor having an annular groove in each lateral face thereof, a plurality of blades in each of said grooves forming a series of buckets, the walls of each groove closing the spaces between the blades at the sides thereof, and a casing having a channel facing each of said grooves, the casing making substantially water-tight joints with each lateral surface of the rotor on the opposite sides of the groove to form 80 a pair of closed fluid raceways. 85

18. A pump comprising a rotor having an annular groove in each lateral face thereof, a plurality of blades in each groove forming a series of buckets, the ends of the blades being substantially flush with the corresponding surface of the rotor at the sides of the groove, and a casing having a channel facing each side of said rotor and making substantially water-tight joints with the surface of the rotor on opposite sides of the groove to form a pair of closed fluid raceways. 95

19. A pump comprising a rotor having in each lateral face an annular groove and a plurality of blades in each of said grooves, the walls of each groove closing the spaces between the blades at the sides thereof, and a casing having an annular channel therein facing each of said grooves and blades and making a substantially water-tight joint with each lateral face of the rotor on opposite sides of the groove to form a pair of substantially closed fluid raceways. 105

20. A pump comprising a casing, a rotatable disc in said casing having annularly arranged blades disposed adjacent but inwardly from the peripheral edge of the disc and forming buckets open to each lateral face of the rotor whereby a continuous annular face lies immediately adjacent said peripheral edge, said casing and disc making a substantially water-tight fit along said face on each side of said rotor, and a groove in each side wall of said casing forming a pair of fluid passages therein on opposite sides of the rotor and opposite the blades, and fluid deflecting means closely fitting a plurality of consecutive blades at the discharge end of the passages whereby sub- 115 120 125 130

- stantial loss of pressure at the discharge ends of the passages is prevented.
21. A pump comprising a casing, a rotatable disc in said casing, said casing having an annular passage formed therein opposite each lateral face of the disc and adjacent its margin, an annular series of blades on said disc spaced from its periphery to engage liquid in each of said passages, said disc and casing having a substantially tight fit on the radially inner and outer sides of said blades whereby movement of liquid radially with respect to each of said passages is resisted, liquid deflecting means closely fitting a plurality of consecutive blades whereby the flow of liquid between the deflecting means and the casing is substantially prevented, and supply and discharge ducts cooperating with said passages.
- 20 22. A pump comprising a casing, a rotatable disc in said casing, said casing having a plurality of annular passages therein of less maximum diameter than the disc and adjacent its margin, a separate annular series of blades on a lateral face of said disc for engaging liquid in each of said passages, pockets on the disc between the blades closed from the periphery of the disc, said disc and casing making a substantially tight fit on the inner side of each of the series of blades whereby movement of liquid radially inwardly from the passages is resisted, and supply and discharge ducts cooperating with said passages.
- 35 23. A pump comprising a casing, a rotatable disc in said casing, said casing having an annular passage therein opposite each lateral face of the disc and adjacent its margin, an annular series of blades on each lateral face of said disc to engage liquid in said passages, pockets on the disc between the blades closed from the periphery of the disc, said disc and casing making a substantially tight fit on the inner side of each series of blades whereby movement of liquid radially inwardly is resisted, there being also a substantially tight fit between the casing and rotor outside each series of blades, a liquid deflecting stop in close working engagement at all times during operation with at least one of said blades, and supply and discharge ducts cooperating with said passages.
- 55 24. A pump comprising a casing, a rotatable disc in said casing, said casing having an annular passage therein opposite each lateral face of the disc and adjacent its margin, a separate annular series of blades on each lateral face of said disc to engage liquid in said passages, pockets on the disc between the blades, said disc and casing making a substantially tight fit on the inner side of the series of blades whereby movement of liquid radially inwardly is resisted, there being also a substantially tight fit between the casing and rotor outside each series of blades, and supply and discharge ducts cooperating with said passages.
- 60 25. A rotary pump comprising a casing having a plurality of fluid raceways, a rotor in said casing having a series of blades for operating upon fluid travelling through each raceway, said casing having an inlet and an outlet duct each communicating directly with each of said raceways, and a liquid deflecting stop making a close working fit with said blades and adapted to maintain a substantial pressure differential at the outlet end of each raceway.
- 70 26. A single-stage rotary pump comprising a casing having a plurality of fluid raceways, and a rotor in said casing having a series of pockets adjacent its margin for operating upon fluid travelling through each raceway, said casing having an inlet and an outlet duct each communicating directly with each of said raceways and fluid deflecting means in the casing adjacent the outlet of each raceway closely engaging a plurality of consecutive blades of the rotor for maintaining relatively large pressure differentials between the outlet and inlet ends of the raceways during operation of the pump.
- 80 27. In a rotary pump, a substantially cylindrical casing, opposed annular passageways near the inner periphery of the casing, a rotor within the casing having pockets on opposite sides aligning with said passageways, inlet and outlet ports each communicating directly with each of said passageways, and liquid stop and deflecting means closely fitting the openings of said pockets for maintaining substantial pressures at the outlet end of the raceways during operation of the pump.
- 90 28. A pump comprising a casing, a shaft mounted therein, a rotor secured to the shaft, a plurality of annular passages in the casing adjacent the periphery of the rotor, said casing having a substantially peripheral supply and a substantially peripheral discharge duct each communicating directly with each of said passages, blades on the rotor for engaging liquid in said passages, and liquid deflecting means making a close working fit with the blades on the rotor and of greater circumferential extent than the distance between successive blades for maintaining substantial pressures at the outlet ends of the passages.
- 100 29. A pump comprising a casing, a shaft mounted therein, a rotor secured to the shaft, a plurality of annular passages in the casing adjacent the periphery of the rotor, said passages being disposed opposite one another and the rotor being positioned therebetween, said casing having a supply and a discharge duct each communicating directly with each of said passages, blades on the rotor for en-
- 110
- 120
- 125
- 130

gaging and propelling liquid through said passages, and liquid deflecting and pressure retaining means adjacent the discharge end of said passages making a close working fit with the blades of the rotor.

30. A rotary pump comprising a casing having at least two annular fluid raceways, a rotor in the casing having a plurality of series of blades one of which series cooperates with each raceway for operating on fluid travelling therethrough, and liquid deflecting means in the casing adjacent the outlet of each raceway for closely engaging a plurality of consecutive blades of the rotor for maintaining relatively large pressure differentials between the outlet and inlet ends of the raceways.

31. A rotor for a pump comprising a metallic disc having a multiplicity of pockets formed in the disc and opening into opposite lateral faces of said disc, said pockets being disposed adjacent to but radially inwardly from the peripheral edge of the disc whereby a continuous annular face lies immediately adjacent said peripheral edge of each side of said disc, a casing for the rotor, radially closed annular raceways formed on each side of the disc by close working fits between said casing and disc, supply and discharge ducts communicating with said raceways, and means adjacent the discharge end of the raceways and of greater circumferential extent than the width of one of said pockets closely fitting the face of said rotor wherein the pockets are formed for maintaining relatively high pressure differentials between the supply and discharge ends of said raceways during operation of the pump.

32. A rotary pump comprising a casing, a rotor mounted therein and defining therewith a liquid raceway on each side of the rotor, liquid propelling blades on the rotor adapted to engage and propel liquid along said raceways, and a stop at one end of said raceways arranged to closely fit a plurality of the blades of the rotor on each side thereof to prevent substantial flow of liquid between the stop and the edges of the blades at the discharge end of said raceways for maintaining relatively high pressure differentials between the supply and discharge ends of said raceways whereby the lateral thrusts produced by liquid under pressure in said raceways are opposing and self compensating and the rotor is substantially relieved from unbalanced axial thrusts.

33. A rotary pump comprising a casing, a rotor mounted therein having annular portions on each side adjacent the periphery making a close running fit with the casing to define therewith a fluid raceway on each side of the rotor adjacent its periphery, liquid propelling blades on the rotor adapted to engage and propel liquid along said raceways, a discharge duct, and means

in the casing closely fitting a plurality of the rotor blades for deflecting liquid from said raceways into the discharge duct and for preventing substantial flow of liquid along said rotor between the blades and said deflecting means whereby unbalanced axial pressures on said rotor are avoided and whereby relatively high pressure differentials are maintained between the inlet and discharge ends of said raceways.

34. A rotary pump comprising a casing, a rotatable disc cooperating therewith to form a plurality of radially closed annular passages remote from the axis of the disc, a multiplicity of liquid engaging pockets formed in said disc to engage liquid in said passages and propel the same therealong, said disc and casing having a substantially liquid tight working fit on the radially inner side of each passage whereby movement of liquid radially inwardly from said passage is substantially prevented, and liquid deflecting means of greater circumferential extent than the width of one pocket closely fitting said pockets for maintaining a relatively high pressure differential between the inlet and the outlet ends of the passages during operation of the pump.

35. A rotary pump comprising a casing, a rotatable disc in said casing, said disc and casing cooperating to form a radially closed annular passage having a close working fit on the inner side of said passage whereby substantial flow of liquid radially inward from the passage is prevented, a multiplicity of liquid engaging and propelling pockets formed in the disc for propelling liquid along said annular passage, and liquid deflecting means circumferentially extending over more than one pocket and closely fitting the face of the pockets of the disc adjacent the discharge end of the passage for preventing substantial flow of liquid between sides of the pockets and the casing adjacent the outlet end of said passage, said passage being of relatively great length with respect to its radial width and being of materially less cross sectional area adjacent the discharge end than adjacent the other end thereof.

36. A rotary pump comprising a casing, a rotatable disc in said casing, said disc and casing cooperating to form a radially closed annular passage having a close working fit on the inner side of said passage whereby substantial flow of liquid radially inward from the passage is prevented, a multiplicity of liquid engaging and propelling pockets formed in the disc for propelling liquid along said annular passage, and liquid deflecting means closely fitting the face of the pockets of the disc adjacent the discharge end of the passage for preventing substantial flow of liquid between the sides of the pockets and the casing adjacent the outlet

end of said passage, said passage being of relatively great length with respect to its radial width and being of progressively smaller effective cross sectional area from the inlet end to the outlet end thereof.

37. A rotor for a pump comprising a metallic disc having an annular series of radially disposed blades on each side thereof, pockets formed in each side of the disc be-

tween said blades, said blades being disposed inwardly from the peripheral edge of the disc and remote from its axis whereby a continuous annular face lies immediately adjacent said peripheral edge.

In testimony whereof, I hereunto affix my signature.

WILLIAM I. DERRICK.
